UNITED STATES PATENT OFFICE.

SAMUEL ROLLAND, OF FLINT, MICHIGAN.

GAS-COCK SHIELD.

Application filed May 2, 1925. Serial No. 27,496.

To all whom it may concern:

Be it known that I, SAMUEL ROLLAND, a citizen of the United States, residing in Flint, in the county of Genesee and State of Michigan, have invented a new and useful Improvement in a Gas-Cock Shield, of which the following is a specification.

My invention relates to a new and useful improvement in a gas cock shield, adapted for use with gas stoves having stop cocks to control the flow of the gas to the burners. It is the purpose of the present invention, to provide a shield which may be moved into position to cover the stop cocks of a gas stove, so as to prevent their undue operation by children and the like.

It is an object of the present invention, to provide a shield of this class, which will be simple of structure, economical of manufacture and highly efficient in use, composed of a minimum number of parts.

Another object of the invention is the provision of a shield of this class comprising two main body portions, swingably mounted upon each other, and adapted for movement into parallel relation with each other when in inoperative position or extending at right angles to each other, when in operative position.

Another object of the invention is to provide a cover plate, swingingly mounted on a supporting plate and adapted to be swung into either horizontal or vertical position.

Another object of the invention is the provision of a cover plate having elongated attachment means for swingingly connecting the cover plate to a vertically extending supporting plate.

Other objects will appear hereinafter.

The invention consists in the combinations and arrangements of parts hereinafter described and claimed.

The invention will be best understood from a reference to the accompanying drawings which form a part of this specification and in which—

Fig. 1 is a front elevational view showing the invention attached to a gas stove, shown in fragment,

Fig. 2 is a sectional view, taken on substantially line 2—2 of Fig. 1,

Fig. 3 is a side elevational view of the invention, showing the cover plate in inoperative position,

Fig. 4 is a side elevational view showing the cover plate in operative position,

Fig. 5 is a sectional view taken on substantially line 5—5 of Fig. 3.

As shown in the drawings, the invention is adapted for use with a gas stove, having a feed pipe 9 for delivering gas to the burners of the stove. The feed pipe 9 is connected by a suitable connection 10 to individual burner pipes 14, a stop cock 11 being interposed between the burner pipe 14 and the delivery pipe 9, said stop cock being controlled by a suitable handle. An air regulator 13 is mounted on the forward end of the individual burner pipe 14. This pipe 14 projects through the forward wall 15 of the gas stove, which is provided with suitable brackets 16 for supporting the cover 17 of the stove. The invention comprises a sheet of metal 18 which is provided, at one end, with the vertically extending flange 19 and the horizontally extending flange 20, these flanges being adapted to lie flush with the end of the plate 18. At the opposite end of the plate 18, lying flush therewith, are flanges 21 and 22 which are similar to the flanges 19 and 20. Secured by screws 24 to the plate 18 intermediate its ends are yokes 23, which are adapted to embrace the delivery pipe 9, a suitable screw 25 being threaded into one of the arms of the yokes, and adapted for engaging the delivery pipe 9 to afford a firm mounting. A cover plate 26 is provided, which is also preferably made of metal and has one end angularly turned as at 27. The opposite end is also angularly turned as at 26', the angularity of this portion 26' being less than the angularly turned portion 27. As shown in Fig. 2, the end of the portion 26, is curled to form an open knuckle. Secured to the undersurface of the plate 26, at opposite ends thereof are strips of metal 28, one end of which is curled as at 29 to form with the plate 26 and its angularly turned portion 27 a knuckle. The opposite end of the strip 28, as shown in Fig. 2, is angularly turned, to form a closure for the open knuckle formed on the end of the angularly turned portion 26'.

As clearly seen in Fig. 1, hangers are provided for attaching the plate 26 to the flanges 19 and 20 and 21 and 22. These hangers comprise U-shaped members 30 having the legs 32 and 33 turned inwardly toward the flanges at opposite sides of the plate 18. As clearly seen in Figs. 1 and 3, the leg 33 of the U-shaped member 30 is engaged in

the knuckle formed by the angularly turned portions 27 and 29. The leg 32 is projected into an opening formed in the flange 19 or in the flange 21.

- 5 Similar U-shaped hangers 34 are provided with inturned legs, one of which is adapted to engage in an opening formed in the flange 22 or 20, the other inturned leg of which is adapted to engage in the knuckle 10 formed by the curled portion of the angularly turned portion 26' and the angularly turned portion 31. The connection is such that the plate 26 may be swung to lie in horizontal position as shown in Figs. 1, 2 15 and 4, or swung to extend vertically as shown in Fig. 3. When it is desired to have access to the handles 12, the plate 26 will be swung into the position shown in Fig. 3. At other times, when it is desired to prevent access 20 to the burners by small children, and the like, the cover plate 26 will be swung to horizontal position, as shown in the drawings. The ends of the flanges 20 and 22 are each pressed out to provide a bead 35. 25 When the cover plate 26 is swung into horizontal position, the U-shaped hangers 34 will ride over the bead 35, the bead 35 serving to press the U-shaped hangers outwardly slightly against their tension and lock the 30 cover plate 26 in operative position. It will be noted that in Fig. 4 the U-shaped hanger 34 is lying substantially horizontal. The bead 35 has a tendency, however, to move this U-shaped supporting member 34 downwardly past center, on account of the inclined sides of the bead 35, so that a locking 35 effect is provided.

It is thus seen that the shield is an effective one for the purpose, and that the number of 40 parts has been reduced to a minimum, so that the cost of manufacture is at a minimum. The arrangement of the hangers is believed to be novel and is effective for the purpose in permitting the plate 26 to swing to its 45 operative or inoperative position.

While I have illustrated and described the preferred form of structure, I do not wish to limit myself to the precise form of structure 50 shown, but desire to avail myself of such variations and modifications as come within the scope of the appended claims.

Having thus described my invention, what I claim as new and desire to secure by Letters Patent is:

- 55 1. A gas cock shield of the class described, comprising a vertically extending supporting plate having a vertically extending and a horizontally projecting flange at opposite ends; a supporting member for mounting 60 said plate on the feed pipe of a gas stove; and a cover plate, adapted, when in inoperative position, to extend parallel to and in close relation with said supporting plate and when in operative position, for extending 65 horizontally in close engagement with said

horizontally projecting flanges; and means for mounting said cover plate on said flanges for permitting the swinging of said cover plate into operative or inoperative position.

2. A gas cock shield of the class described 70 comprising a supporting plate, adapted for mounting in vertical relation upon the delivery pipe of a gas stove; a vertically extending flange at opposite ends of said plate projecting inwardly toward said delivery 75 pipe; a supporting arm projecting horizontally from the upper end of each of said flanges inwardly of said delivery pipe; a cover plate, adapted when in operative position for lying in close engagement with said supporting arms, and for extending vertically 80 in close relation to said supporting plate, when in inoperative position; and means connecting said plate to said flanges and said supporting arms for permitting the swinging 85 movement of said plate to either position.

3. A gas shield of the class described, comprising a plate, adapted for mounting in vertical position on the delivery pipe of a 90 gas stove; a vertically extending flange at each end of said plate projecting inwardly toward said delivery pipe; a supporting arm projecting inwardly toward said delivery pipe from the upper end of each of said 95 flanges, said supporting arm being horizontal; a cover plate adapted, when in operative position, for lying horizontally in close engagement with said supporting arms, and when in inoperative position for extending vertically in close relation to said supporting 100 plate; means for connecting one of the edges of said cover plate at its opposite ends to each of said flanges; and means for connecting the opposite edge of said cover plate at its opposite ends to each of said supporting arms, said connecting means permitting the free swingable movement of said cover plate to operative or inoperative position.

4. A gas shield of the class described, comprising a plate, adapted for mounting in vertical position on the delivery pipe of a gas stove; a vertically extending flange at each end of said plate projecting inwardly toward said delivery pipe; a supporting arm projecting inwardly toward said delivery pipe from the upper end of each of said flanges, said supporting arm being horizontal; a cover plate adapted, when in operative position, for lying horizontally in close engagement with said supporting arms, and when in inoperative position, for extending vertically in close relation to said supporting 115 plate; means for connecting one of the edges of said cover plate at its opposite ends to each of said flanges; and means for connecting the opposite edge of said cover plate at its opposite ends to each of said supporting arms, said connecting means permitting the free swingable movement of said cover plate to operative or inoperative position.

120 5. A gas shield of the class described, comprising a plate, adapted for mounting in vertical position on the delivery pipe of a gas stove; a vertically extending flange at each end of said plate projecting inwardly toward said delivery pipe; a supporting arm projecting inwardly toward said delivery pipe from the upper end of each of said flanges, said supporting arm being horizontal; a cover plate adapted, when in operative position, for lying horizontally in close engagement with said supporting arms, and when in inoperative position, for extending vertically in close relation to said supporting 125 plate; means for connecting one of the edges of said cover plate at its opposite ends to each of said flanges; and means for connecting the opposite edge of said cover plate at its opposite ends to each of said supporting arms, said connecting means permitting the free swingable move- 130

ment of said cover plate to operative or inoperative position, said supporting arms being provided, on their outer surfaces, adjacent one end, with a bead for engaging the connecting means attached to said supporting arms for resisting the movement of said cover plate from operative to inoperative position.

5. A gas cock shield of the class described, comprising a front plate; means for mounting said plate on the delivery pipe of a gas stove, said plate extending, when mounted, vertically; a vertically extending flange at each end of said plate projecting inwardly from the inner face thereof; a supporting arm projecting inwardly from the upper end of each of said flanges and extending horizontally; a cover plate having one end angularly turned substantially at right angles thereto and the opposite end angularly turned, at a less angle, the extreme end of said angularly turned portion last mentioned being curled to form an open knuckle; a strip mounted on the undersurface of said cover plate transversely thereof, having its end angularly turned to co-operate with said angularly turned portions of said cover plate, to provide a knuckle at opposite sides thereof; U-shaped hangers, each having one leg pivotally mounted in an opening formed in one of the flanges, and the opposite leg engaging in one of the knuckles formed at one edge of said cover plate; a U-shaped hanger having one of its legs projecting into an opening formed in 35 said supporting arm, and its free leg projecting into the other knuckle of said cover plate to permit the swinging of said cover plate into inoperative position, so as to extend vertically in close relation to said front plate, and to permit the swinging of said cover plate into operative position so as to lie horizontally in close relation to said supporting arms; and a bead on the outer surface of each of said supporting arms for 40 engaging one pair of said hangers for resisting movement of said cover plate from operative to inoperative position.

10 15 20 25

In testimony whereof, I have signed the foregoing specification.

SAMUEL ROLLAND.
